UNITED STATES PATENT OFFICE

JOHN S. STOKES, OF HUNTINGDON VALLEY, PENNSYLVANIA, ASSIGNEE TO STOKES AND SMITH COMPANY, OF PHILADELPHIA, PENNSYLVANIA, A CORPORATION OF PENNSYLVANIA

BOX

Application filed June 30, 1930. Serial No. 484,833.

My invention relates to the formation of boxes, cartons, containers, or the like, herein-after generically termed "boxes" from a plurality of separate components attached to each other during a box-forming operation.

In accordance with my invention, box components adapted to form, for example, the bottom and side walls of a box are cut in succession from a continuous strip, as a roll, of 10 box material; preferably prior to the severing of the strip, it is scored, specifically transversely, to define the box panels or walls and thereafter, adhesive coated sheet material is applied to the scored strip with portions 15 thereof projecting beyond it.

At a box forming station, each of the components is brought into proper box-forming relation with other box components, which may likewise be cut from continuous strip, 20 and the projecting adhesive-coated material folded to attach the separate components to each other to form a box.

Further in accordance with my invention, to either or both sides of the strips of box material may be applied covering material, as paper, to improve the appearance of the finished box. The application is preferably prior to severance of the box material so that a single cutting operation produces a covered 30 component.

Also in accordance with my invention and more specifically, the box is provided with a cover formed by box material extending from one and preferably several of the components. 35 Subsequent to insertion of contents into the formed box, the cover extensions or panels are brought into over-lapping relation to close the container and are held in position as by adhesive. Preferably, the top of the 40 closed box is capped, as by a sheet of paper, or the like, whose edges projecting beyond the top of the box are wiped into adhesive engagement with the vertical box walls.

My invention also resides in the methods 45 for forming boxes hereinafter described and claimed.

For an understanding of my invention, reference is to be had to the accompanying drawings in which in perspective:

50 Fig. 1 illustrates continuous strips of box

and sheet material with abutting, scoring and adhesive applying apparatus.

Fig. 2 shows a prepared main-box component.

Fig. 3 is a view of the box component of 55 Fig. 2 bent along its scoring.

Fig. 4 illustrates rolls of box material for minor box components with cutting, scoring, and box-forming apparatus.

Fig. 5 discloses minor box components held 60 against form-block structure aligned with major or main box component.

Figs. 6 to 11 inclusive illustrate successive steps of forming a composite box from a group of components. 65

Fig. 12 shows a continuous strip of cover material with adhesive applying and cutting mechanism.

Figs. 13 to 15 illustrate successive steps of applying a cover or cap to the box of Fig. 11. 70

Fig. 16 shows a modified form of prepared main box components in which the projecting strip material is notched.

Fig. 17 illustrates the blank of Fig. 16 75 bent along its scoring.

Fig. 18 is similar to Fig. 4.

Fig. 19 is similar to Fig. 5 showing how-ever the modified form of main component in alignment with the form block.

Figs. 20 to 25 illustrate successive steps of 80 forming a composite box utilizing the component of Fig. 16.

Figs. 26 to 30 disclose successive steps of preparing and applying a notched cap to the box of Fig. 25. 85

Figs. 31 and 31a show, continuous strips of box material, covering material, and attaching material with scoring, cutting, and adhesive applying mechanism.

Figs. 32 and 32a are views of opposite sides 90 of the covered main box component.

Fig. 33 shows the blank of Fig. 32 bent along its scoring.

Fig. 34 shows rolls of box material for forming minor box components, covering material with scoring and cutting mechanism.

Fig. 35 discloses the minor covered components held against form block structure aligned with the main component of Fig. 32. 100

Referring to Fig. 1, the continuous strip S fed, for example, from a roll 1, is of suitable box material as cardboard, strawboard, or the like, and is of width corresponding to a dimension, as length or width of boxes to be produced. The scoring knives 2, 3, 4, and 5 are adjustably secured to the shaft 6, the distance between the central knives 3, 4 corresponding, for example, to the width of the box and the distance between each of the outer knives, 2, 5, and the adjacent inner knife corresponding to the vertical height of a box. While the strip S is stationary, the shaft 6 carrying the scoring knives is moved transversely across the strip scoring it as indicated by the dotted lines to define the side panels P, P, and the bottom panel B. Preferably the rolls 7 engage the opposite side of the strip over the scoring knives and move therewith to hold the strip against movement away from the knives.

After the scoring operation, and while the knives are out of engagement with the strip, it is moved to the right as viewed in Fig. 1. During this forward movement, attaching strips 9, preferably cut, as by knives 14, from strips "A" removed from rolls 10, are applied to the under surface of the strip S lengthwise thereof, and with a substantial part of the strips 9 extending outwardly beyond the edges of strip S. As indicated, the top surface of the strips "A" contact with a roll 11 supplied with adhesive as by a transfer roll 12. The coated strips which are wiped into engagement with the strip S, as by a roll 13, are cut by the knives 14, or the like, when the length of the strips corresponds with the distance between the scoring knives or creasing rolls 2 and 5, or otherwise stated and in the example shown, to twice the vertical height of the box plus the width of the box bottom. The attaching strips are cut when the strip S is stationary and preferably substantially simultaneously with the cutting of strip S by knives 8, 8 or equivalent.

As the box to be formed is to be provided with cover structure, the total length of the component which is shown in Fig. 2, is greater than the length of these strips. The strip S with the attaching pieces 9 applied thereto, is moved between the knives until the distance between the trailing ends of the attaching pieces and the knives 8 corresponds to the width of the cover panel 15. The knives are then actuated to sever the strip to form the main blank component M of Fig. 2. The distance between the leading edges of the strips 9 being fed toward the knives 8, and the knives 8, is equal to the width of the cover piece or extension 16 of a blank, as yet not severed.

The preparation or formation of main box components is continuous, for example, when the strip S is stationary, the knives 8 may be moving to cut the strip to form one com-

ponent while at the same time the scoring knives are moving transversely of the strip in a region which subsequently becomes another box component. Further, while the leading edge of the strip of box material with attaching strips 9 applied thereto, is being moved away from the knives 8, other strips of attaching material are being applied toward the portion of the strip S moving toward the knives 8.

Referring to Fig. 4, the minor components m, m of the box may be cut from continuous strips s of box material by the sets or pairs of knives 17, 17. As the strips s are fed from the rolls 18 to a point beyond the knives corresponding to the width of the box, the scoring knives or creasing rolls 19 score or crease them lengthwise, the rolls 20, bearing against the upper surface of the strips preventing movement of the strips. Preferably the strips are fed toward a wrapping station, as toward the form block structure F. The minor components m, m, which each form a side panel p and a cover section 21, are swung upwardly and inwardly from the position shown in Fig. 4 against the ends of the form block structure F, as in Fig. 5, where they are held. The main component M, as indicated in the same figure, is aligned with the form block so that upon relative movement of the two, the minor and major components of a box assume their box forming position as shown in Fig. 6, the bottom edges of the panels P and p of the components lying in substantially the same plane, or in abutting relation with each other.

Thereafter the vertical projecting parts of the strips 9 are folded inwardly as shown in Fig. 7, to overlie and adhesively engage the panels p of the end or minor box components, whereupon, the central or horizontal portions of the strips 9 projecting beyond the bottom panel B of the main component, are folded upwardly into adhesive engagement with the minor components, the box thus formed having the appearance shown in Fig. 8. The form block F is then withdrawn from the composite box thus formed. The side and bottom panels of the main component are held in proper relation to each other, and the end walls formed by the minor components are held in proper position to each other and attached to the main component by the strips 9.

The operations thus far described are preferably continuous in the sense that there is no substantial interruption or delay between the succeeding steps. For example, a plurality of main components M are not accumulated, stored, and then withdrawn from storage for use. The adhesive securing the strips 9 to the main components is still moist or unset when the strips are wiped into engagement with the minor components m.

which have been positioned in box forming relation with the main component.

Further, the preparation of a main blank M and the minor components m for association therewith may be substantially concurrent so that groups of components, each adapted to form a box, are delivered in succession to the form-block. During the formation of a box by one group, another group 10 of complementary components is being prepared, and specifically several main components may simultaneously be in various stages of completion.

The open top boxes thus formed may be stored, or as each is formed, an article Z, Fig. 8, may be inserted therein, whereupon the top extensions 21, 21, of the minor components m are turned inwardly, preferably simultaneously. Thereafter, the panel sections 15 16 and 15 are folded inwardly in overlapping position, and are held by adhesive applied to one or the other, specifically the longer flap 15, by a distributing roller 22 supplied by a transfer roller 23.

25 The appearance of the closed box of Fig. 11 is improved by capping or covering it with paper or suitable material. The capping or covering piece 24 is cut from a strip T, removed from a roll 25, by knives 26. The 30 piece 24 which was coated with adhesive by roller 27 as it moved toward the knives, is applied to the closed top of the box with the edges extending therebeyond on all sides. Preferably the piece is not cut from the strip 35 until after it has been applied to the closed box top. The projecting ends of the capping piece 24 are folded downwardly into engagement with the end walls of the box, Fig. 13, and then inwardly against the side walls 40 of the box, Fig. 14. The projecting sides of the capping piece 24 are then folded downwardly into engagement with the side walls of the box and the inwardly turned end portions, Fig. 15, to complete the box.

45 The prepared main component of Fig. 16 is similar to that of Fig. 2 except that the strips 9 are notched opposite the scoring forming the bottom panel B to form independently movable flaps. This notching 50 may be effected before the main component has been severed from the strip S, Fig. 1, or thereafter. The main component when bent along its scoring appears as in Fig. 17.

While the notching may be afforded by applying the strips 9 in sections corresponding in length to the bottom and sides preferably the strips are applied as indicated and thereafter notched or cut.

As in the preceding modification the minor 60 components m may be cut from continuous strips s and each pair in turn is held against the form block structure with the bottom and vertical edges of the components flush with the sides and bottom of the form block.

65 With the minor and major components held

against the form block in proper position, the strip 9 is manipulated to attach the major and minor components to each other and to hold them permanently in box forming position. Specifically, the side flaps of strips 9 70 are folded inwardly preferably simultaneously and thereafter the bottom flaps are folded upwardly, preferably simultaneously. The notching of the attaching strips as indicated, avoids the gusset folds at the lower corners of 75 the box, as the central portions of the strips 9, which project beyond the bottom panels of the box are severed from the vertical projecting portions of the strip.

Similarly, the cover piece 24 may be 80 notched, Fig. 27, so that the flaps e of the projecting ends of the cap piece 24 may be folded inwardly against the side wall of the box, Fig. 29, without effecting movement of any part of the side projections f of the cap piece, which are subsequently folded downwardly, covering the flaps e and engaging the side walls of the box between the strips 9.

85 For some classes of work it is desirable to produce a box which is covered, as by paper, either inside or outside or both. This may be effected, as shown in Fig. 31, by applying suitable covering material, as paper, to either or both the upper and underside of the strip S. As indicated, after the strip S is scored, 90 and before the attaching strips 9 are applied thereto, strip-like covering material, for example, the strips L and C, of paper, and of width corresponding to the width of strip S, is brought into adhesive engagement with the surfaces of the strip. The adhesive is applied to the undersurface of lining strip L and the upper surface of the covering strip C, by the distributing rolls 25 and 26 respectively, supplied with adhesive by the transfer rolls 27 and 28, the underneath strip C, covering the surface of strip S adapted to form the outside of the box concealing the score. Thereafter, the attaching or setting strips 9 are applied to the undersurface of the cover strip projecting beyond the edges thereof as in the preceding modifications. The knives 8 sever the strip to form the prepared cover component M1 of Fig. 32, which when bent along the scoring assumes the appearance of 105 Fig. 33.

110 Particularly when the box is capped, the covering strips C, c applied to the strips of box material do not overlie the cover sections 15, 16, and 21. This not only saves lining material but in the case of cover sections 15 and 16 of the main components affords a better surface for the reception of adhesive. The rolls 30, when the cover sections 21 of the minor or end wall components are left 115 exposed, are of less width than the rolls 18 and 29. The roll of covering material for the main component however is the same width as the rolls of box and lining material, the knives 35 cutting the strip C of proper 120

length and at proper time to extend between the scoring or creasing effected by knives or rolls 2 and 5.

Similarly, the strips *s* from which the minor components *m1* are cut, Fig. 34, are covered on either or both sides. To that end, the lining strip 1 and the covering strip *c*, removed from rolls 29 and 30 after passing over the coating rolls 31 and 32 supplied with adhesive by the transfer rolls 33 and 34, are brought into engagement with the upper and lower surfaces of the strips, subsequent to the score. The knives 17, cut the composite strip to form prepared and covered minor components *m1*. The covered minor components are held against the form block structure F in box forming relation to the covered main component M1.

The operation, at least thus far, is preferably continuous, that is without substantial delay between the succeeding steps so that the adhesive attaching the covering strip to the box strip and the adhesive upon the projecting parts of the attaching strips is unset when the components are arranged in box-forming position or relation.

The steps of forming the box by folding the attaching strips 9 to hold the components in box forming position, and the subsequent steps of closing the box and applying a covering cap thereto, is the same as in the prior modifications. If desired, the covering strips may be notched, in which case the steps are clearly illustrated by Figs. 20 to 30 of a previously described modification.

In all modifications the components after being prepared, are delivered in groups, each group consisting of the necessary components to form a box, to the wrapping station, and utilized without elapse of substantial interval of time. There is no storage of the prepared components which involves transportation and repeated handling with consequent increased cost of production and increased waste. Further there is no waste of material as occasioned by use of one-piece blanks. A composite box of this type is broadly described and claimed in my co-pending application Serial No. 88,231, filed February 15, 1926.

While all of the steps may be manually performed, at least many of them may be effected mechanically. For example, the manipulation of the strips 9 to attach the box components may be effected by a box machine similar, for example, to that of my co-pending application Serial No. 147,405, filed November 10, 1926. Further the cutting of the minor components from continuous strip and delivering them to a form block to which is delivered a prepared major component with projecting attaching strips, may be effected by mechanism similar to that shown in co-pending Rider application Serial No. 425,751, or Rider application Se-

rial No. 460,859 in which the major component is registered upon supporting structure from which it is transported to the form block in register therewith, and against which the minor components are held. 70

It will be understood that my invention is not restricted to the modifications specifically described but is commensurate in scope with the appended claims.

For brevity in the appended claims the term "scoring" is intended to mean not only scoring in which the fibres of the box material are cut but also "creasing" in which the panels are defined and the blank bent along creases formed by blunted rolls which do not cut the fibres. 75 80

What I claim is:

1. The method of making boxes which comprises, scoring a strip of box material to define a wall section, adhesively applying sheet material to said strip with a portion thereof projecting from said wall section, thereafter severing said strip beyond the scoring to form a prepared component having an integral cover section, bringing other components into engagement with said prepared component in position to form walls of a box, and folding the portion of sheet material projecting from the wall section of the first component into adhesive engagement with said other components to attach them in said position, with the cover section of said first component free from attachment to said other components by said sheet material. 90 95

2. The method of making boxes which comprises, adhesively applying sheet material to a strip of box material with portion thereof extending beyond opposite sides of said strip, thereafter severing said strip to form a prepared box component, bringing other component box structure into engagement with said opposite sides of the prepared component in position to form box walls, and folding the portions of sheet material extending from the sides of the first component into adhesive engagement with said structure. 100 105 110

3. The method of making boxes which comprises, adhesively applying strips of sheet material to opposite sides of a strip of box material with parts thereof extending beyond the box material strip, severing the strip to form a box component, bringing detached components into engagement with said sides of the first component in position to form walls of a box, folding said strips into engagement with the corresponding detached components to attach them to said first component and to hold all of said components in said position. 115 120

4. The method of making boxes which comprises, transversely scoring a strip of box material to define panel sections adapted to form side walls and bottom of a box, adhesively applying continuous strips of sheet material to opposite sides of said strip of 125 130

- box material with parts of each projecting beyond said panel sections, severing said strip to form a box component, bringing other components adapted to form other side walls of the box into engagement with said first component in box-forming position, and folding said projecting parts of said strips into adhesive engagement with said other components to attach them to said first component in box forming position. 5. The method of making boxes which comprises, transversely scoring a strip of box material to define a panel section adapted to form the bottom of a box, adhesively applying sheet material to opposite edges of said strip within said section and on either side thereof to an extent corresponding to vertical height of the box, the material projecting outwardly from said edges, severing said strip to form a box component, bringing end wall box structure into engagement with said component in box-forming position, and folding the outwardly projecting sheet material into adhesive engagement with said end wall structure. 6. The method of making boxes which comprises, transversely scoring a strip of box material to define panel sections adapted to form the bottom and opposite side walls of a box, adhesively applying sheet material to said strip between said scoring with part thereof projecting outwardly from opposite edges of said strip, cutting said strip beyond said scoring to form a box component with integral cover structure, bringing end wall box structure into engagement with said component in box-forming position, and folding the outwardly projecting sheet material into adhesive engagement with said end wall structure. 7. The method of making boxes which comprises, scoring a strip of box material, feeding the strip toward a region in which it is cut to form a box component, during said feeding movement adhesively applying sheet material to said strip with part thereof extending beyond the strip, delivering the box component cut from said strip to a wrapping station, substantially simultaneously delivering complementary box structure to said station, and at said station with said box component and box structure in box-forming position, folding the sheet material projecting from the former into adhesive engagement with the latter to attach them in said position. 8. The method of making an unwrapped composite box which comprises, adhesively applying to opposite edges of a box component adapted to form the bottom and opposite side walls of a box, continuous strips of sheet material projecting beyond said edges, cutting the strips of sheet material, thereafter bringing separate components adapted to form another pair of side walls of said box into engagement with said first component having said strips thereon in position to form a box, and folding the projecting portions of said strips into adhesive engagement with the corresponding separate components. 9. The method of making an unwrapped composite box which comprises, scoring a strip of box material transversely to define the bottom and side wall panels of a box component, adhesively applying strips of sheet material to said strip along opposite edges thereof at right angles to said scoring and projecting in part beyond said edges, bringing separate components adapted to form another pair of side walls into adhesive engagement with said edges of the first component in position to form a box, and folding the projecting portions of said strips into adhesive engagement with the corresponding separate components. 10. The method of making boxes which comprises, scoring a strip of box material transversely thereof, feeding sheet material from a roll, adhesively applying the sheet material to said strip to project in part beyond said strip in the same direction as the scoring, cutting said strip and said sheet material to form a prepared box component, bringing complementary box structure into engagement with said component in position to form a box, and attaching said complementary box structure to said box component by folding the projecting sheet material into adhesive engagement with said complementary box structure. 11. The method of making boxes which comprises, feeding a strip of box material from a roll thereof, scoring the strip transversely, feeding the scored strip toward a station at which it is cut to form a box component, feeding sheet material from a roll thereof, adhesively applying the sheet material to said scored strip during feeding thereof and to project beyond the edge of the strip, cutting the strip and the sheet material to form a box component, bringing complementary box structure into engagement with said component in position to form a box, and attaching said complementary box structure to said component by folding the projecting sheet material into adhesive engagement with said complementary box structure. 12. The method of making an unwrapped box which comprises, feeding strips of box material from rolls thereof, adhesively applying sheet material to one of said strips to project beyond opposite edges thereof, cutting said strips to form a group of box components, delivering said group of components to a forming station, and at said station and while said components are in box forming position, attaching them to each other by folding the projecting sheet material into adhesive engagement with an adjacent detached component.

13. The method of making boxes which comprises, preparing box components by feeding a strip of box material from a roll thereof, adhesively applying sheet material to said strip with part thereof extending beyond edges of the strip, substantially simultaneously scoring a part of the strip to which sheet material has not yet been applied and cutting the strip to form a box component with attached projecting sheet material, concurrently with preparation of said components preparing complementary box components by feeding box material from rolls thereof, cutting components from said rolls, delivering in succession to a box forming station a group of said components, and at said station in succession attaching the components of each group to each other to form a box by folding of the projecting part of said sheet material. 70
14. The method of making boxes which comprises, preparing box components by feeding a strip of box material from a roll thereof, adhesively applying sheet material to said strip with part thereof extending beyond edges of the strip, substantially simultaneously scoring a part of the strip to which sheet material has not yet been applied and cutting the strip to form a box component with attached projecting sheet material, concurrently with preparation of said components preparing complementary box components by feeding box material from rolls thereof, cutting components from said rolls, delivering in succession to a box forming station a group of said components, and at said station in succession attaching the components of each group to each other to form a box by folding of the projecting part of said sheet material, and concurrently with formation of a box by one group of elements preparing other components for delivery to said station. 85
15. The method of making boxes which comprises, scoring a strip of box material, adhesively applying sheet material to the scored strip with a portion thereof projecting beyond said strip, notching the projecting material adjacent said scoring to form independently movable flaps, bringing thereafter complementary box structure into engagement with said component, in box-forming position, and folding said flaps into adhesive engagement with said complementary box structure to attach it to said component in box-forming position. 100
16. The method of making boxes which comprises, scoring a strip of box material to define panel sections adapted to form the bottom and a pair of vertical walls of a box, adhesively applying continuous strips of sheet material to opposite edges of the scored strip with part of each projecting therebeyond, notching the projecting parts of said strips to form independently movable flaps, bringing thereafter separate components adapted to form another pair of box sides into engagement with said opposite edges of said first component in position to form a box, folding the vertical projecting flaps inwardly into engagement with corresponding separate components, and thereafter folding the horizontal projecting flaps upwardly into engagement with corresponding separate components. 115
17. The method of making boxes which comprises, scoring a strip of box material, covering at least one surface of the strip with sheet material, adhesively applying other sheet material to said strip with part thereof projecting beyond opposite edges of said strip, cutting the covered strip with projecting sheet material to form a box component, covering at least one surface of another strip of box material, cutting the covered strip to form a second box component, bringing said covered box components into position to form adjacent walls of a box, and folding the strip material projecting from the first component into adhesive engagement with said second component. 130
18. The method of making boxes which comprises, scoring a strip of box material, covering at least one surface of the scored strip with sheet material, adhesively applying strips of sheet material to opposite edges of the scored, covered strip to project in part beyond said edges, thereafter cutting the strip to form a box component, covering at least one surface of another strip of box material, cutting the covered strip to form a second box component, bringing said covered components in position to form adjacent box walls, and folding the strip material projecting from the first covered component into adhesive engagement with said second covered component. 145
19. The method of forming closed boxes which comprises scoring strips of box material to define wall and cover sections, adhesively applying sheet material to one of said strips with part thereof projecting outwardly only from a wall section, cutting said strips to form components of a box, bringing said components into box forming position, folding the projecting sheet material to attach only the adjacent wall sections of otherwise detached components, and thereafter folding and attaching the cover sections of the components to close the box. 160
20. The method of forming closed boxes which comprises, scoring strips of box material to define wall and cover sections, adhesively applying sheet material to one of said strips with part thereof projecting outwardly from a wall section, cutting said strips to form components of a box, bringing said components into box forming position, folding the projecting sheet material to attach adjacent wall sections of otherwise detached 175

components, thereafter folding and attaching the cover sections of the components to close the box, adhesively applying a strip of sheet material to the closed top of the box, 5 severing the strip to form a capping piece with flaps projecting beyond the box top, and folding the flaps into adhesive engagement with wall sections formed by the attached components of the box to seal the box 10 and further to unite said components.

21. The method of making a box which comprises, adhesively applying sheet material to a box compartment adapted to form the bottom and opposite vertical walls of a 15 box with portions thereof extending beyond the sides of said component, transversely cutting the projecting portions to form flaps projecting from opposite sides of said bottom and vertical walls, bringing end wall components in engagement with said first component in box-forming position, and folding flaps at each end of the box into adhesive engagement with the corresponding end wall component and into overlapping engagement 20 with each other.

22. The method of making a box which comprises, adhesively applying sheet material to a box component adapted to form the bottom and opposite vertical walls of a box 25 with portions thereof extending beyond the sides of said component, transversely cutting the projecting portions to form flaps projecting from opposite sides of said bottom and vertical walls, bringing end wall components 30 in engagement with said first component in box-forming position, folding the flaps projecting from vertical walls at each end of the box into adhesive engagement with the corresponding end wall component, and there- 35 after folding the flaps projecting from the box bottom, into adhesive engagement with the corresponding end wall component and the previously folded vertical flaps.

23. The method of making a box which 40 comprises, adhesively applying tab strips along opposite edges of a box component adapted to form the bottom and opposite vertical walls of a box to project in part beyond said edges, transversely cutting the projecting tab portions to form flaps extending 45 from opposite sides of said bottom and vertical walls, bringing end wall components in engagement with said first component in box-forming position, and folding tab flaps 50 at each end of the box into adhesive engagement with the corresponding end wall components and into overlapping engagement.

24. The method of making boxes which 55 comprises, adhesively applying sheet covering material and tab strips to a strip of box material with the tab strips projecting beyond the box strip, applying sheet covering material to other strips of box material, cutting the composite strips to form components 60 of a covered box, assembling the group of

components in box-forming position, and folding the projecting tab portions to unite said components in box-forming position.

25. The method of making boxes which 65 comprises, feeding box material from a roll thereof, transversely scoring the strip, applying covering material fed from a roll thereof to the scored strip, applying strip-like tab material fed from rolls thereof to project in part beyond the edges of the edges 70 of the covered, scored strip, severing the composite strip to produce box components each adapted to form the bottom and side walls of a box, feeding other strips of box material from rolls, applying covering material 75 thereto from rolls thereof, cutting the composite strips to form end wall components, assembling groups of said components in box-forming relation, and uniting the components of each group to form a covered box 80 by the projecting tab material.

26. The continuous method of making 85 boxes which comprises cutting box components cutting box components from strips of box material, covering the strips with sheet 90 covering material before said cutting, adhesively applying tab material to at least one of the covered strips before said cutting to project therefrom, transporting in succession groups of said components to a station, and at said station uniting the components of each group by said projecting tab 95 material.

27. The method of making boxes which 100 comprises covering strips of box material as they are fed from rolls, severing one of said covered strips to form box components each adapted to form the bottom and side walls of a box, severing another of said covered strips to form components each adapted to 105 form a box end, arranging a group of components in box-forming relation, and attaching said components in said relation by tab strips to form a covered box.

28. The method of making boxes which 110 comprises feeding strips of box material and strips of covering material from rolls into adhesive engagement to form covered strips, severing one of the covered strips as formed to produce box components each adapted to 115 form the bottom and side walls of a box, severing another of the covered strips as formed to produce box end components, assembling a group of components in box-forming relation, and attaching said components while in said relation by tab strips 120 to form a covered box.

29. The method of making boxes which 125 comprises feeding strips of box material from rolls, severing one of said strips to form components each adapted to form the bottom and side walls of a box, severing another of said strips to form components each adapted to form a box end, applying covering material to at least one of said strips before 130

severance thereof, arranging a group of components in box-forming position, and attaching said components in said position by tab strips overlying corners of the box
5 formed thereby.

30. The method of making boxes which comprises feeding strips of box material from rolls, severing said strips to form components each adapted to form at least one vertical wall of a box, applying covering material to at least one of said strips before severance thereof, arranging a group of components in box-forming position, and attaching said components in said position by tab strips overlying corners of the box formed thereby.

31. The method of making boxes which comprises feeding strips of box material from rolls, scoring one of said strips, severing said one of said strips to produce box components each adapted to form the bottom and at least one vertical wall of a box, severing another of said strips to produce components each adapted to form another vertical box wall, arranging a group of components in box-forming position, and attaching said components in said position by tab strips overlying corners of the box formed thereby.

CERTIFICATE OF CORRECTION.

Patent No. 1,911,212.

May 30, 1933.

JOHN S. STOKES.

It is hereby certified that error appears in the printed specifications of the above numbered patent requiring correction as follows: Page 1, line 51, for "abutting" read cutting; page 6, lines 50-51 and 66, claims 15 and 16, respectively, strike out the word "thereafter" and insert the same before the word "bringing" in same lines; page 7, line 75, claim 25, strike out the words "of the edges"; and line 89, claim 26, strike out "cutting box components"; and that the said Letters Patent should be read with these corrections therein that the same may conform to the record of the case in the Patent Office.

Signed and sealed this 28th day of November, A. D. 1933.
